CLAIM

The ornamental design for a temple for eyeglasses as shown
and described.

DESCRIPTION

FIG. 1 is a front perspective view of a temple for eyeglasses
showing my new design;

FIG. 2 is a rear perspective view of thereof;

FIG. 3 is a front view of thereof;

FIG. 4 is a rear view of thereof;

FIG. 5 is a top plan view of thereof;

FIG. 6 is a bottom plan view of thereof;

FIG. 7 is a right side view of thereof;

FIG. 8 is a left side view of thereof;

FIG. 9 is a sectional view taken along the line 9-9 of FIG.
3;

FIG. 10 is a sectional view taken along the line 10-10 of FIG.
8 of the portion defined by the line 10'-10' of FIG. 3;

FIG. 11 is a sectional view taken along the line 11-11 of FIG.
3;

FIG. 12 is a perspective view in a state of use with
environment;

FIG. 13 is a front view in a state of use with environment;
and,

FIG. 14 is a top view in a state of use with environment.

The evenly spaced broken lines depict portions of the temple
for eyeglasses and forms no part of the claimed design. The
additional evenly spaced broken lines seen in FIGS. 12-14
depict environment and forms no part of the claimed design.
The alternate long and short dash lines are for the purpose
of disclosing the boundaries of the claimed design.

1 Claim, 14 Drawing Sheets
